UNITED STATES PATENT OFFICE

HARRY MAURICE BATEMAN, OF BURWOOD, AUSTRALIA, NEW SOUTH WALES

METAL HOLDFAST

Application filed February 5, 1930, Serial No. 426,170, and in Australia December 5, 1929.

This invention relates to friction grips of the type in which one arm of the grip is forced into close contact with the material to be held, and is adapted for use in constructional metal work to prevent movement in one direction of a plate, girder, beam, or rail, and is particularly adapted to prevent creep of rails on railway lines.

The invention comprises the use of flat or of angle steel pieces and of U shaped bars of suitable cross section which pass through holes formed in the steel pieces and preferably spaced so that the distance between adjacent edges of the holes is less than the width of the material to be held. The bars are adapted to be partially rotated into gripping contact with the material to be held.

In the accompanying drawings which illustrate the invention:

20 Fig. 1 is a sectional elevation of a holdfast in position on a rail.

Fig. 2 is a plan of the same.

Fig. 3 is a side elevation of the same.

25 Fig. 4 is an end elevation of a U shaped bar.

Fig. 5 is a perspective view of a flat steel piece and U bars.

The upper horizontal flange 10 of an angle steel piece, which is of greater length than 20 the width of the base of a rail 11, is provided with spaced holes 12 on each side of the rail positioned so that the rail lies over a portion of each hole.

A U shaped bar 13 of slightly smaller diameter than a hole 12 is adapted to be inserted 25 in each hole and faces 14 are formed on the inner sides of the ends of the arms of the bar to increase the area of contact of the bar with the rail and angle steel piece 10.

20 The upper arm 15 of the bar may be of greater length than the lower arm 16.

In application an angle steel piece is placed under the rail so that each hole 12 is partly under the base of the rail and the vertical flange 17 of the angle piece is in contact with the vertical face of a sleeper 18. A U bar is 25 inserted in each hole 12 with the arms 15, 16 projecting in the direction opposite to that of the normal creep of the rail. The upper arm 50 15 of each bar is then pushed inwards to-

wards the web 19 of the rail to grip the sloping face 20 of the foot flange. While the arm 15 is being swung into position the elbow of each bar travels outwards in the hole 12 to make close contact with the angle piece, and the lower arm 16 is drawn up against the lower face of the flange 10 of the angle piece which is thus firmly clamped to the rail.

Any tendency of the rail to move forward or creep increases the grip of the U bars on the rail and the forward pressure is transmitted by the angle piece to the sleeper 18 so that creep is prevented.

For a hundred pound rail each angle piece may be approximately nine inches in length 65 with flanges two inches wide and three-eighths of an inch in thickness. In this case a contact area of about eighteen square inches is made between each angle piece and a sleeper. The U bars may be of about one inch in diameter. 70

For other classes of constructional metal work the angle steel piece may be replaced by a flat steel piece 21 provided with spaced holes 12 and U shaped bars.

The dimensions of the steel piece and the diameter of the U bars may be varied for application to different sections of rails, girders, beams, and the like.

I claim:

1. A metal holdfast comprising a steel piece, spaced holes formed in the steel piece, and a U shaped steel bar adapted to be rotated in each hole.

2. A metal holdfast comprising a steel piece, spaced holes formed in the steel piece, a U shaped steel bar adapted to be rotated in each hole, and a flat surface on the inner face on the end of each arm of the bars.

3. A metal holdfast comprising an angle steel piece, a horizontal flange forming one face of the angle piece, spaced holes in the horizontal flange and a U shaped bar of smaller diameter than the hole inserted in each hole and adapted to be rotated therein.

4. A metal holdfast comprising an angle steel piece, a horizontal flange forming one face of the angle piece, a vertical flange forming another face of the angle piece, spaced holes formed in the horizontal flange, a U 100

shaped steel bar adapted to be rotated in each hole and having its upper arm of greater length than its lower arm, and a flat surface on the inner face of the outer end of each arm of the bar.

5. A metal holdfast comprising a steel piece, holes formed in the steel piece and spaced at a distance less than the width of the material to be held, and a U shaped steel bar adapted to be rotated in each hole.

In testimony whereof I have signed my name to this specification.

HARRY M. BATEMAN.
